UNITED STATES PATENT OFFICE.

JOHN ANDREW WALSH, OF WAREHAM, ASSIGNOR TO THE TREMONT NAIL COMPANY, OF WEST WAREHAM, MASSACHUSETTS.

PILE-BOX.

SPECIFICATION forming part of Letters Patent No. 311,696, dated February 3, 1885.

Application filed June 28, 1884. (No model.)

To all whom it may concern:

Be it known that I, JOHN A. WALSH, a citizen of the United States, residing at Wareham, in the county of Plymouth and State of Massachusetts, have invented certain new and useful Improvements in Closed Boxes for Containing Iron, Steel, &c., of which the following is a full, clear, and exact description, reference being had to the accompanying drawings, 10 forming part of this specification, in which—

Figure 1 is a perspective view of the bottom of my improved box. Fig. 2 is a like view of the side pieces. Fig. 3 is a perspective view of the bottom with the side pieces 15 placed thereon. Fig. 4 is a plan view of the box complete without a cover. Fig. 5 is a side elevation of the same with the cover in place. Figs. 6 and 7 are modifications to be referred to.

20 My invention relates to certain improvements in the manufacture of closed boxes for containing iron and steel to be welded in rolls or "squeezers," or under the hammer, or by any other well-known process; and my invention 25 consists in the peculiar arrangement, construction, and combination of devices, to be hereinafter more fully set forth, and specifically pointed out in the claims.

The object of my invention is to provide a 30 cheap and rapid means for manufacturing boxes by which scrap iron and steel will be practically protected from the air during the process of welding.

In heating scrap-iron all exposed surfaces 35 are oxidized, and a loose pile of this material, admitting air throughout its interior, exposes a much larger area of surface to be oxidized than the same weight of iron will do if enclosed in an iron box, because in the latter 40 case the exterior surface only is oxidized; hence there is great economy in heating the material in closed boxes, which can be constructed without the expenditure of much time or money, and also as scrap-steel cannot 45 be welded upon a large scale except by excluding the air. If heated in the open air, the steel will melt or burn before it reaches a welding heat. To remove these difficulties is the purpose of my invention.

50 The material used in constructing my boxes is common "muck-bars," so called, being

puddled iron rolled from the puddled ball directly into bars. Scrap-bars or other more costly materials may be used for special purposes; but for ordinary work I prefer to use 55 the material above referred to; and in making the boxes I also prefer to use the widths of muck-bars commonly rolled in all muck-mills—that is to say, bars three inches, four inches, and six inches wide. Other widths 60 may be used when the dimensions of the desired pile require it.

In order to more fully describe my invention, I will now describe one of my boxes to be used as hereinbefore stated, the material 65 placed therein to be rolled into nail-plate in a mill with grooved breaker-rolls, the grooves about twelve and one-half inches wide.

The bottom of the box is made of two pieces of muck-bar, each thirteen inches long, six 70 inches wide, and of any desired thickness. These bars, which I have designated in the drawings by the letters A and B, are shown in Fig. 1 lying side by side, so as to form a substantial bottom, while the top or cover L, 75 Fig. 5, is constructed precisely in the same manner. The four sides are made from two pieces, C and D, of muck-bar four inches wide, each cut to a suitable length, and each formed with two bends, so as to obtain substantially a 80 L-shaped form, and by this construction each piece contains one full side and a part of each of two other sides, as shown in Figs. 2 and 3. The bending of these side pieces may be done by any simple machinery.

In putting the box together the bottom pieces, A and B, are laid upon a piling-bench, and the side pieces, C and D, placed upon them in the manner shown in Fig. 3, and the ends *e f f* of the bent portions being placed in 90 close contact with each other; and in order to make a good weld the pieces F F, (see Fig. 4,) which are also made of muck-bars about four inches wide, may, if desired, be used, being placed in such manner that they overlap the 95 ends of the side pieces, C and D. Then the box is complete, with the exception of the cover before referred to.

I do not wish to limit myself to the exact form of the side pieces, C and D, as shown in 100 Figs. 2, 3, and 4, in which the bent portions are shown as being of the same length, because,

as shown in Fig. 6, these bent portions are made of unequal lengths; and, again, in Fig. 7 we show it is not necessary that the main portion of the side pieces and the bent portions should be of the same length, as in this figure (7) the portions G are somewhat longer than the portion D, and the bent portions H of the side piece C are comparatively short and pass between the ends of pieces G. In this case the welding pieces F may be dispensed with, if desired.

In using boxes of the description herein set forth, the side pieces, C and D, having been placed upon the bottom A and B, the space inclosed by the side pieces is filled with scrap iron or steel, or both, and the cover L placed in position. This cover may be large enough to slightly overlap the side pieces and completes a good substantial box without the aid of other fastenings; and, if desired, the iron bottom A B may be replaced with a wooden one, as is customary in heating open scrap-piles, and the iron sides will come in closer contact with the bottom of the furnace as the wooden bottom burns away, and the entrance of air will thus be prevented.

I am aware that boxes with three sides have been made of a single bent bar for the pur-

pose of containing scrap to be welded; but they simply hold the material together in convenient form for welding without regard to the exclusion of air, and they are left open for the free admission of air. This I do not claim as my invention, as the principal feature of my box is the exclusion of the air; but

What I do claim, and desire to secure by Letters Patent, is—

1. A device for containing iron or steel scrap, the same consisting of a bottom divided into two or more parts, A and B, the L shaped side pieces, C and D, and a cover, L, substantially as and for the purpose herein described.

2. The combination, with the bottom and cover, each consisting of two or more independent pieces, A and B, of the L-shaped side pieces, C and D, constructed and arranged to operate substantially as described.

3. In a box for containing scrap iron or steel, and in combination with the top and bottom, as described, the welding pieces F, by means of which the side pieces, C and D, are joined together, substantially as herein set forth.

JOHN ANDREW WALSH.
